LAWN SPRINKLER

Earl O. Griswold, Atlanta, Ga.

Application July 26, 1950, Serial No. 11,419

Term of patent 7 years

(Cl. D91—1)

To all whom it may concern:

Be it known that I, Earl O. Griswold, a citizen of the United States, residing in Atlanta, in the county of Fulton and State of Georgia, have invented a new, original, and ornamental Design for Lawn Sprinkler, of which the following is a specification, reference being had to the accompanying drawing, forming part thereof, and wherein:

Fig. 1 is a perspective view of a lawn sprinkler embodying my new design.

Fig. 2 is a side view of the sprinkler shown in Fig. 1.

Fig. 3 is a front end view of the sprinkler shown in Fig. 1.

Fig. 4 is a top plan view of the sprinkler shown in Fig. 1.

Fig. 5 is a view of the side opposite that shown in Fig. 2.

I claim:

The ornamental design for a lawn sprinkler, substantially as shown.

EARL O. GRISWOLD.
